UNITED STATES PATENT OFFICE.

FRANK D. F. WALTERS AND ERNEST R. WATERS, OF PORTLAND, COLORADO.

YOKE FOR PULVERIZING AND GRINDING MILLS.

1,248,215.

Specification of Letters Patent. Patented Nov. 27, 1917.

Application filed May 25, 1917. Serial No. 179,871.

To all whom it may concern:

Be it known that we, FRANK D. F. WALTERS and ERNEST R. WATERS, citizens of the United States, residing at Portland, in the county of Fremont and State of Colorado, have invented certain new and useful Improvements in Yokes for Pulverizing and Grinding Mills, of which the following is a specification.

10 Our invention has relation to pulverizing or grinding mills, and our improvements relate particularly to the yoke supporting the fanning means and pusher arms.

One object is to provide means for stiffening the vertical projecting arms, which support the fanning means thus reducing and eliminating crystallization which is so marked in the present design.

A further object is to improve the construction of the pusher arms, whereby it is possible to eliminate the pusher pins, said pins having been used to hold the pusher on the pusher arm of the yoke.

In the accompanying drawings:

25 Fig. 1 is a sectional elevation of the pulverizer.

Fig. 2 is a perspective view of the yoke and pusher arms.

Fig. 3 is a top plan view thereof.

30 Fig. 4 is a horizontal section through the pusher arm and the pusher.

Fig. 5 is a perspective view of the pusher proper.

Fig. 6 is a perspective view of the lower fan blade.

Fig. 7 is a perspective view of the upper fan blade.

Referring to the drawings, 1 represents the body portion of the yoke, projecting vertically therefrom are the arms 2-2, which are adapted to be connected together at their uppermost ends by a suitable web 3, by which all possible vibration of the arms 2-2 is eliminated, which prevents possible crystallization of the arms thereby lengthening the life of the yoke with respect to these parts.

In the webs 3 and intermediate between the vertical projecting arms 2-2 is a portion 4 with a straight or flat surface, in said flat surface are two holes 4' to be ground to size which allows for riveting the fan blade 3', as shown in Fig. 7 to the yoke.

At the lower end of said vertical projecting arms 2-2 is a portion 5 with straight or flat surface, in said flat surface are two

holes 5' obliquely arranged and ground to size which allows for riveting the fan blade 3' as shown in Fig. 6 to the yoke.

The base portion of the yoke is provided with a square orifice 6 which is adapted to receive a suitable driving shaft.

It is a common practice to provide the base of the yoke with pusher arms which are provided with suitable pushers at the outer ends thereof, which are in turn keyed thereto and adapted to push balls around in the mill in a horizontal plane. This construction, however, is subject to more or less objection in view of the breaking of the pins, keys or bolts, which in turn do great damage to the mill.

The present construction consists of a plurality of pusher arms 7 extending radially from the base portion of the yoke. The outer ends of these arms are preferably formed into hooked members 8, which members turn inwardly, thereby forming a recess 9. Adapted to be received upon the outer ends of these pusher arms, is a pusher 10. This pusher is provided with a pocket 11, which is adapted to receive the pusher arm, and is also provided with ears 12, which are adapted to surround the pusher arms in such a manner as to hold the pusher in place, as disclosed in Figs. 3 and 4. As will be seen these pushers are so arranged that they are held on by centrifugal force as the yoke is rotated, there being no pins or the like used in order to secure the pusher in place. When it is desired to remove or replace the pushers they are moved laterally off the arm thereby withdrawing the hooked portion therefrom.

Having thus described the nature and object of our invention, we claim:

1. A yoke comprising a base portion, a plurality of pusher arms projecting therefrom, and a plurality of pushers removably secured thereto and held thereon by centrifugal force.

2. A yoke comprising a base portion, a plurality of pusher arms projecting therefrom and provided at their outer ends with hooked portions, and a plurality of pushers adapted to be received upon the outer ends of said pusher arms, said pushers being provided with pockets which receive the hooked portions of the pusher arms thereby preventing the pushers from being thrown off by centrifugal force.

3. A yoke comprising a base, a plurality

of arms each having a flat surface and each provided with a series of holes, said arms extending vertically from said base, and annular webs cast integral with and at the top 5 of the vertically extending arms and forming an open space between said arms and web, the webs being each provided with a series of flat surfaces provided with a se-

ries of holes said flat surfaces occupying a position between the vertical planes of said 10 vertically extending arms.

In testimony whereof we affix our signatures.

FRANK D. F. WALTERS.
ERNEST E. WATERS.
